Term of patent 14 years

(Cl. D30—1)

FIG. 1.

FIG. 2.

FIG. 5.

FIG. 3.

FIG. 6.

FIG. 4.

FIG. 7.

FIG. 1 is a side elevational view of a combined gun barrel lock-up ramp and sight, embodying my new design, the pistol in broken lines being shown for illustrative purposes only.

FIG. 2 is a top plan view thereof.

FIG. 3 is a side elevational view thereof on an enlarged scale.

FIG. 4 is a bottom view thereof.

FIG. 5 is a rear end elevational view thereof.

FIG. 6 is a front end elevational view thereof.

FIG. 7 is a perspective view thereof.

The undisclosed side of the combined gun barrel lock-up ramp and sight is substantially the same in appearance as the side shown.

I claim:

The ornamental design for a combined gun barrel lock-up ramp and sight, substantially as shown and described.
